BLADE HOLDER

Charles A. Gerlach, St. Petersburg, Fla.

Application October 29, 1953, Serial No. 27,376

Term of patent 7 years

(Cl. D22—3)

To all whom it may concern:

Be it known that I, Charles A. Gerlach, a citizen of the United States, residing at St. Petersburg, in the county of Pinellas and State of Florida, have invented a new, original, and ornamental Design for a Blade Holder, of which the following is a specification, reference being had to the accompanying drawing, forming a part thereof.

Fig. 1 is a side view of a blade holder, showing my new design, the opposite side thereof presents a substantially similar appearance except for the absence of the blade holding slots, and

Fig. 2 is a front edge view of the blade holder shown in Fig. 1.

The razor blade, shown in broken lines on the drawing, is merely for purposes of illustration.

I claim:

The ornamental design for a blade holder, as shown and described.
